(57) **CLAIM**

The ornamental design for a baseball tee as shown and described.

DESCRIPTION

FIG. 1 is a front, top, right side perspective view of a baseball tee, showing my new design

FIG. 2 is a bottom, rear, left side perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of the area labeled 9 in FIG. 1;

FIG. 10 is an enlarged view of the area labeled 10 in FIG. 1;

FIG. 11 is an enlarged view of the area labeled 11 in FIG. 2;

FIG. 12 is an enlarged view of the area labeled 12 in FIG. 2; and,

FIG. 13 is an enlarged view of the area labeled 13 in FIG. 2.

The broken lines in the drawings depict portions of the baseball tee that form no part of the claimed design. The dot-dash broken lines encircling portions of the baseball tee in FIGS. 1 and 2 and illustrated in enlarged view in FIGS. 9-13 form no part of the claimed design.

1 Claim, 13 Drawing Sheets
